[57] CLAIM

The ornamental design for a toy space vehicle, substantially as shown and described.

DESCRIPTION

FIG. 1 is a perspective view of a toy space vehicle showing my new design;

FIG. 2 is a top plan view thereof;

FIG. 3 is a side elevational view thereof, the side opposite being substantially a mirror image thereof;

FIG. 4 is a bottom plan view thereof;

FIG. 5 is a front elevational view thereof;

FIG. 6 is a rear elevational view thereof; and
